M. H. HART

HOSE NOZZLE

Filed Aug. 10, 1923

UNITED STATES PATENT OFFICE.

MILTON H. HART, OF HARTFORD, CONNECTICUT.

HOSE NOZZLE.

Application filed August 10, 1923. Serial No. 656,727.

This invention relates to hose nozzles such for instance as are used in fighting fires and among the objects of the invention is the provision of a simple device of this character which can be properly and efficiently held to an elevating ladder or to the side of a hose vehicle and by the use of which proper distribution of the water can be effected.

In the drawings accompanying and forming part of the present specification there is shown somewhat in detail an advantageous form of embodiment of the invention which, to enable those skilled in the art to practice the same, will be set forth fully in the following description. I am not restricted to this disclosure. I may depart therefrom in a number of respects within the scope of the invention defined by the claim following said description.

Referring to said drawing:

Fig. 1 is an elevation of a nozzle involving the invention.

Fig. 2 is a side elevation of the upper portion of the same.

Fig. 3 is a bottom plan view.

Like characters refer to like parts throughout the several views of the drawings.

The device involves in its structure a base member such as that denoted in a general way by 2 and which may comprise several members.

The base member 2 is coupled by the sleeve 12 to the lower end of the forked member 13. Said forked member 13 comprises sections 14 and 15 which are in fact duplicates of each other and which are welded or otherwise rigidly connected at their lower ends which are screwed into the sleeve 12. The sections 14 and 15 are tubular and they divide the stream of water received from the base member 2 into two branches or streams which afterwards unite. The sections 14 and 15 are rigidly connected at their upper ends by the head piece 16 which has a tubular neck 17 that receives within it the pipe section 18, having on its extreme upper end the coupling 19 which has threaded onto it the nozzle 20. The head piece also has laterally extended hubs that project through openings in the sides of the sections 14-15 and

that receive nuts by means of which the head piece is rotatably secured to the sections 14-15.

The structure may be either sustained by a ladder or by the side of a hose cart or something of a similar nature. For this purpose one of the members of the base 2 may have rigid with it the hooks 21 which are adapted to engage over the rung 22 of a ladder or some other part to be held closely thereto by the cams of the cam levers 23, which are supported for movement about vertical axes by the bars 24, the tails of the levers being pressed inwardly and between pins or studs, as 25 and the bars 24, as represented in Fig. 3 in which position said cams lock or fasten the nozzle in a rigid position and against accidental removal although the upper structure may be variously adjusted as will hereinafter be noted.

The branches 14 and 15 of the forked member 13 are closed on their outer sides by the caps or disks 26 which are connected rigidly by the cross bar 27, extending through and secured to the discs 26.

It will be remembered that the tubular portion or neck 17 has been described as having the pipe 18 in detachable threaded relation with it. This neck or tubular extension 17 is an upward extension of the fitting or head 16 of hollow construction, having upon it the lateral neck 29. Water when on flows upwardly through the branches 14 and 15 into the fitting 28 and by its neck 17 into the pipe 16 where it passes into the tubular nozzle 20 to be distributed as may be desired.

A nozzle constructed as shown in Fig. 1 in connection with a hose pipe (not shown) can be carried up a fire ladder and can be attached in the manner set forth to a rung. When in this position it is in readiness for use. The pipe 18 can be swung down on the pin 27 to get the stream at the point desired. The pipe 18 in connection with the forked member 13 can be easily turned so that the action of the appliance becomes in effect universal.

What I claim is:

A hose nozzle comprising, in combination, 100

a base member, similar lateral hooks rigidly mounted on opposite sides of the base member in spaced parallel relation and projecting in the same direction beyond an
5 other side of said base member for engagement with a support, supporting bars rigid with said opposite sides of the base member

and cam levers pivoted on the supporting bars and engageable with the support to draw the hooks into firm engagement with 10 said support.

In testimony whereof I affix my signature.

MILTON H. HART.
